UNITED STATES PATENT OFFICE.

WARREN B. BUCKLEY, OF GLENS FALLS, NEW YORK.

BICYCLE-SADDLE.

SPECIFICATION forming part of Letters Patent No. 536,013, dated March 19, 1895.

Application filed September 12, 1894. Serial No. 522,782. (No model.)

To all whom it may concern:

Be it known that I, WARREN B. BUCKLEY, a citizen of the United States, residing at Glens Falls, county of Warren, and State of New York, have invented certain new and useful Improvements in Bicycle-Saddles, of which the following is a specification.

The invention relates to such improvements and consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

Figure 1 of the drawings is a top plan view of my improved saddle. Fig. 2 is a similar view with the leather seat detached, showing the spring-frame. Fig. 3 is a side elevation of the part shown in Fig. 2. Fig. 4 is a vertical section taken on the broken line 4-4, in Fig. 1. Fig. 5 is a similar section taken on the broken line 5-5, in Fig. 1.

My improved saddle is specially adapted and designed for a lady's bicycle.

The frame shown in Figs. 2 and 3, is made of a single length of spring-wire of suitable diameter, preferably about three-sixteenths of an inch, the ends of the wire forming the attaching shanks A, A. These shanks are bent at their ends so as to provide each shank with laterally projecting offsets A'. The shanks are to be secured to the bicycle frame in the usual well known manner by a clip, not shown, and the offsets effectually prevent the shanks from turning in either direction under the clip, when in use. By having two lateral and oppositely projecting offsets on each shank, the ordinary clip usually applied to a straight wire can be used.

The clip need not engage the offsets, but being in close proximity thereto, the offsets on each shank will act independently of each other to prevent the wire from turning either way under the clip, even though it should become quite loose.

The rear coils A²— form the main springs of the saddle. The small coils A⁸— coiled in a reverse direction relatively to the rear coils form auxiliary springs and tend to keep the

seat in a horizontal position. That portion of the wire which connects the small coils passes rearwardly from the small coils approximately to the forward edges of the large coils, forming the side-supports A⁴—, then on approximately straight lines to the longitudinal middle part of the frame, forming the rear support A⁵—, then forward beyond the line of the small coils to form the loop, or middle support A⁶—. The normal position of all these supports is such that they occupy approximately the same horizontal plane, which plane is slightly above the horizontal plane of the upper edges of the larger coils, as shown in Fig. 3. Fitted upon these supports is the seat B— which is made of leather, canvas, or other flexible material.

The seat material is shaped to conform to the general outline of the side and back supports, and the edges B'— bear upon the side supports, and the rear edge B²— upon the rear supports.

The front edge B³— has its middle part projected forwardly at B⁴— to cover the middle support A⁶—.

The edges of the seat material may be secured to the wire in any known manner, as by rivets C—, or by a stiffening rim D— secured to the edge of the material and adapted to be forced over and back of or beneath the wire, as shown in Fig. 4.

The pommel-saddle commonly in use on bicycles, affords no outside support for the limbs of the rider, and in some instances has seriously and permanently injured lady riders.

My improved saddle affords a support for opposite sides of each lower limb and prevents the unnatural and excessive outward and disjointing strain upon the limbs of the rider occasioned by the pommel form of saddle.

The leather or seat material of my improved saddle, being flexible, yields sufficiently to form a slight depression between each side support and the middle support, thereby giving more prominence to the side supports.

The forward portion of the middle support is shown curved slightly downward at A⁷—.

When the flexible seat is secured at its edges only upon the wire supports, the forward portion of the middle part is free to slide transversely of and upon the middle support

at the forward end of the latter, so that depressions in the seat between the middle support and the side supports will vary when in use, the depression of either limb of the rider 5 causing an increased depression in the seat on the side of the depressed limb, and a corresponding elevation in the seat on the opposite side, on which side the limb of the rider is elevated, whereby the seat is made to adjust itself in large degree to the position of the rider's limbs.

When desired, the loop A⁶— which forms the middle support may be dispensed with, the forward edge of the seat being stiffened 15 or reinforced by a cross-bar B⁶— extending from one side support to the other, as shown in Fig. 5, and indicated by dotted lines B⁷— in Fig. 1.

What I claim as new, and desire to secure 20 by Letters Patent, is—

1. A bicycle-saddle frame composed of an integral spring-wire, and comprising a pair of attaching-shanks, a pair of relatively large

spring-coils, one coil on the rear end of each shank and in vertical plane therewith, a pair 25 of relatively small spring-coils connected with the large coils respectively by forwardly diverging portions of the wire, a seat-support projecting rearwardly from and connecting the small coils, and a middle-support projecting from the rear part of the seat-support forwardly to a position in line with, and midway between, the small coils, substantially as described.

2. In a bicycle-saddle, the combination with 35 a spring-wire frame having a middle and separate side supports of a flexible seat secured to the respective side supports and movable transversely of and on the middle support, substantially as described.

In testimony whereof I have hereunto set 40 my hand this 4th day of September, 1894.

WARREN B. BUCKLEY.
